CLAIM

(51) **LOC (10) Cl. 21-01**

The ornamental design for a controller with removable thumbstick attachment, as shown and described.

(52) **U.S. Cl.**

USPC **D21/333; D14/401**

DESCRIPTION

(58) **Field of Classification Search**

FIG. 1 is a front perspective view of a controller with removable thumbstick attachment showing our new design;

USPC ..... D14/496, 401, 435, 474, 483, 217, 137, D14/138, 160, 168, 356, 203.1–203.8, 507; 345/156, 169, 173–179, 905; 715/727–729, 715/864, 700, 706, 719; 710/1, 5, 8; 713/1, 600; 455/1.1, 1.7, 73, 344–347, 93, 95, 455/3.01–3.06, 550.1, 573.1; 370/342–344; 369/1, 2, 6–12; 463/51–57, 40–47, 1, 463/29–35; D21/324, 328, 333; 273/148 B

FIG. 2 is a top view thereof;

CPC A63F 13/00; A63F 13/02; A63F 9/00; G06F 17/00; G06F 19/00

FIG. 3 is a front view thereof;

See application file for complete search history.

FIG. 4 is a rear view thereof;

(56) **References Cited**

FIG. 5 is a right side view thereof;

U.S. PATENT DOCUMENTS

FIG. 6 is a left side view thereof;

D368,936 S 4/1996 Goto
D398,214 S 9/1998 Yui

FIG. 7 is an exploded front perspective view thereof with the thumbstick detached from the base;

FIG. 8 is a top view thereof;

FIG. 9 is a front view thereof;

FIG. 10 is a rear view thereof;

FIG. 11 is a right side view thereof;

FIG. 12 is a left side view thereof; and,

FIG. 13 is a bottom view thereof.

(Continued)

The broken line showing of the remainder of the controller with removable thumbstick attachment is for environmental purposes only and forms no part of the claimed design.
